[57] CLAIM

The ornamental design for a barbecue grill, as shown and described.

DESCRIPTION

FIG. 1 is a perspective view of a barbecue grill with the hinged top in an open position showing my new design; FIG. 2 is a front elevational view thereof; FIG. 3 is a side elevational view thereof; FIG. 4 is a top plan view thereof; and FIG. 5 is a bottom plan view thereof.

The bracket shown in broken lines in FIG. 1 is for illustrative purposes only and forms no part of the claimed design.

FIG. 1

FIG. 2

FIG. 3

FIG. 4

FIG. 5
